(57) **CLAIM**

The remote control user interface with thin curved profile, as shown and described.

DESCRIPTION

FIG. 1 is a perspective view illustrating the ornamental characteristics of a remote control user interface according to the present design;

FIG. 2 is a top view of the view of the remote control user interface having the present design;

FIG. 3 is a bottom view of the remote control user interface; and,

FIG. 4 is a side view of the remote control user interface.

The broken line in FIGS. 1 and 2 indicates that the surface within the outer perimeter is not part of the claimed design.
